DISH OR SIMILAR ARTICLE

Charles H. Pomeroy, San Antonio, Tex.

Application May 12, 1948, Serial No. 146,328

Term of patent 14 years

(Cl. D44—10)

To all whom it may concern:

Be it known that I, Charles H. Pomeroy, a citizen of the United States, residing at San Antonio, in the county of Bexar, and State of Texas, have invented a new, original, and ornamental Design for a Dish or Similar Article, of which the following is a specification, reference being had to the accompanying drawing, forming part thereof, and in which

Figure 1 is a perspective view of a dish or similar article, showing my new design.

Fig. 2 is a top view.

Fig. 3 is a detailed section on line 3—3 of Fig. 2.

I claim:

The ornamental design for a dish or similar article, as shown.

CHARLES H. POMEROY.
